UNITED STATES PATENT OFFICE.

CHARLES A. LINDSTRÖM, OF PITTSBURG, PENNSYLVANIA, ASSIGNOR TO PRESSED STEEL CAR COMPANY, OF PITTSBURG, PENNSYLVANIA, A CORPORATION OF NEW JERSEY.

CAR CONSTRUCTION.

No. 903,488.

Specification of Letters Patent.

Patented Nov. 10, 1908.

Application filed April 15, 1908. Serial No. 427,192.

To all whom it may concern:

Be it known that I, CHARLES A. LINDSTRÖM, of Pittsburgh, northside, Allegheny county, Pennsylvania, have invented certain new and useful Improvements in Car Construction, of which the following is a full, clear, and exact description, reference being had to the accompanying drawings, in which like characters refer to like parts, and in 10 which—

Figure 1 is a sectional elevation of so much of the car construction as is necessary to illustrate my invention. Fig. 2 is a plan view of a portion of same; Fig. 3 is a sectional view on the line 3—3, Fig. 1; Fig. 4 is a detail face view of a casting forming a part of the structure; Fig. 5 is an end elevation of the same; Fig. 6 is a sectional end elevation of the same; Fig. 7 is a detail plan view of a modified form of casting; Fig. 8 is a like view of still another modification; Fig. 9 is a detail face view of castings shown in Figs. 7 and 8; and Fig. 10 is a detail end elevation showing still another modification 25 of the casting.

An object of the present invention is to provide a novel form of connection between a car underframe beam and the wall, side or end sheeting of a car.

30 The invention is especially adapted to that class of cars known as "general service gondolas" in which the car bottom is made up of a number of drop doors and in which said doors are closed through the medium 35 of a bodily movable shaft connected to said doors in any suitable manner and adapted to support said doors in closed position.

More specifically stated, the invention consists of a casting forming the connecting medium between the car underframe beam and the wall of the car.

In the type of car above mentioned the use 45 of a casting as a connection between a car underframe beam and the wall of the car is especially desirable in that it enables the formation of a suitable guide slot for the said bodily movable shaft and reinforced connecting flanges or angles all in one and the same piece or casting.

50 The use of a casting as a connecting medium between a car underframe beam and the car side where the bottom of the car is not composed of drop doors results advantageously in that reinforced connecting flanges or angles of sufficient number and

position may be made in a single piece or casting.

Incidental to all types of cars where a casting of the character herein shown and described is employed, is a reduction of 60 parts, a stiffer construction and a cheaper construction.

With the foregoing advantages in view, the following detailed description will be more firmly appreciated:

Referring now in detail to the drawings, 1 represents the center sill structure of the car, 2 an underframe beam, cross-bearer or header, 3 the car wall or side sheeting and 4 a car stake.

5 is a casting forming the connecting medium between the side or wall 3 and stake 4 and the cross-bearer, header or beam 2. Casting 5 is here shown as provided with a slot 6 designed to receive and guide movement of 75 the shaft shown in my Patent No. 833,402, dated October 16, 1906, and entitled "Steel car construction." In said patent this slot was formed in plates which were riveted to 80 sides or faces of cross-bearers, beams or headers to register with slots in said beams. In the present case the beam, cross-bearer or header 2 is bifurcated at 2^a at its end so that the slot 6 in casting 5 is unobstructed. Casting 5 is provided with a flange 5^a to which 85 is riveted or secured the upper flange 2^b of beam, cross-bearer or header 2, the beam, cross-bearer or header 2 extending practically to the end of casting 5 and being riveted through its tines, at the bifurcation, to the 90 casting 5. Casting 5 is likewise provided with oppositely extending flanges 5^b which are adapted to be riveted to the stake 4 as shown in Fig. 1, and car side sheeting is brought down, bent under and riveted to the 95 flange 2^b and flange 5^a. Casting 5 may also be provided with other suitable strengthening flanges or ribs to reinforce it.

The casting thus far described is adapted to be riveted or secured to one side or face of beam, cross-bearer or header 2. If desired, the upper flange 5^a of the casting may extend the entire length (Fig. 9) of the casting instead of being abbreviated as shown in Fig. 1, which flange 5^a may be depressed or deflected downwardly to form a seat for the flange 2^b so that the upper surface of the flange 2^b is brought on a level or in plane with the upper surface of the forward portion of the flange 5^a, making a flat seat for 110

the turned-under end portion of the car side sheeting 3. With a casting thus constructed the beam, cross-bearer or header 2 need not extend as far out over the casting 5. If desired, the casting may furthermore have its web deflected so that the forward portion of the web of the casting 5 and the center of the car stake is brought in a direct line with the web of beam, cross-bearer or header 2. 10 This shape is shown in Fig. 8.

As shown in Fig. 10, the casting 5 is formed with but one of the flanges 5^b, the other flange 5^b being formed by riveting an angle to the casting.

15 As shown in Fig. 6, the perforation 6 is shown with an extended or widened wall projecting, if desired, through bifurcation 2^a to form a wide bearing for the shaft to be located thereon.

20 Having thus described my invention, the following is what I claim as new therein and desire to secure by Letters Patent:

1. A connection between a car underframe beam and wall consisting of a flanged member secured to said beam and having a shaft guide slot formed therein.

25 2. A connection between a car underframe beam and wall consisting of a flanged ribbed member secured to said beam and to said wall and having a shaft guide slot formed therein.

30 3. A connection between a car underframe beam and a car wall structure consisting of a member secured to said beam and provided with a horizontal flange secured to the car wall and a vertical flange secured to the car stake.

35 4. In car construction, a beam having a bifurcated end, a flanged reinforced slotted

casting riveted to the bifurcated portion of 40 said beam and to the wall and stake of the car.

5. In car construction, an underframe beam, the car wall, a car stake and a flanged reinforced casting connecting said beam, car 45 wall and stake and having a slot therein with a widened or extended wall.

6. In car construction, a car underframe beam slotted at its end, a casting secured to said beam having a slot therein in line with the slot in said beam and secured to the car wall and stake.

7. In car construction, an underframe beam, a casting secured thereto and having oppositely extending vertical flanges and a horizontal flange, a car stake secured to said vertical flanges and the car wall secured to said horizontal flange.

8. A connection between a car underframe and wall consisting of an independently 60 formed member with a shaft guide slot formed therein.

9. In a car, the underframe and a car wall stake in combination with an independently 65 formed member connected to said underframe and stake and formed with a shaft guide slot formed therein.

10. A connection between a car cross-bearer and stake consisting of an independently formed member with a shaft guide 70 slot formed therein.

The foregoing specification signed at McKees Rocks, Allegheny county, Pennsylvania, this 6th day of April, 1908.

CHARLES A. LINDSTROM.
